(57) **CLAIM**

The ornamental design for a vehicle wheel rim, as shown and described.

DESCRIPTION

FIG. 1 is a right perspective view of the invention. FIG. 2 is a front elevation view of FIG. 1. FIG. 3 is a left perspective view of FIG. 1. FIG. 4 is a left side elevation view of FIG. 1, the right side, top plan, and bottom plan views being mirror images thereof due to the circular shape. FIG. 5 is an enlarged partial top perspective view of FIG. 1, as an illustrative aid, noting the details therein. FIG. 6 is an enlarged partial bottom perspective view of FIG. 1, as an illustrative aid, noting the details therein. FIG. 7 is a right perspective view of a second embodiment of the invention. FIG. 8 is a front elevation view of FIG. 7. FIG. 9 is a left perspective view of FIG. 7. FIG. 10 is a left side elevation view of FIG. 7, the right side, top plan, and bottom plan views being mirror images thereof due to the circular shape. FIG. 11 is an enlarged partial top perspective view of FIG. 7, as an illustrative aid, noting the details therein; and, FIG. 12 is an enlarged partial bottom perspective view of FIG. 7, as an illustrative aid, noting the details therein. The broken line showing of the rear portion of the rim, the central hub area, the bolt holes, the center hole and the valve stem hole is included for the purpose of illustrating environment and forms no part of the claimed design.
